UNITED STATES PATENT OFFICE.

CLAYTON B. FERGUSON, OF GLENHAZEL, PENNSYLVANIA.

RAIL-JOINT.

991,436.

Specification of Letters Patent.

Patented May 2, 1911.

Application filed February 13, 1911. Serial No. 608,182.

To all whom it may concern:

Be it known that I, CLAYTON B. FERGUSON, a citizen of the United States of America, residing at Glenhazel, in the county of Elk 5 and State of Pennsylvania, have invented certain new and useful Improvements in Rail-Joints, of which the following is a specification, reference being had therein to the accompanying drawing.

- 10 This invention relates to rail joints and the objects of my invention are to provide positive and reliable means in a manner as will be hereinafter set forth whereby the confronting ends of two rails can be connected to prevent vertical and lateral displacement of one rail relatively to the other, and obviate the necessity of using bolts and nuts for connecting splice bars to the sides of the rails.
- 20 Further objects of my invention are to provide a fastening means for the confronting ends of the rails which will become more positive the longer the rail joint is used and to accomplish the above results by a mechanical construction that is simple, durable 25 and highly efficient for the purposes for which it is intended.

These and such other objects as may hereinafter appear are attained by the novel construction, combination and arrangement of parts as will be hereinafter more specifically described and then claimed.

In describing the invention in detail, reference will be had to the accompanying drawing wherein like numerals of reference 35 denote corresponding parts throughout the several views in which:—

Figure 1 is a side elevation of the rail joint. Fig. 2 is a longitudinal sectional view 40 of the same. Fig. 3 is a cross sectional view of the rail joint. Fig. 4 is a perspective view of a detached key. Fig. 5 is a perspective view of a detached splice bar.

The reference numerals 1 denote ties or 45 sleepers supporting the confronting ends of two rails, said rails having the base flanges 2 thereof provided with depending transverse ribs 3 adapted to rest upon the ties 1 and support said rails. The ribs 3 are provided only at the ends of the rails to support 50 said rails in an elevated position to prevent the keys, to be hereinafter referred to, from contacting with the ground or ballast of road bed. The rails have the web

portion 4 thereof provided with transverse 55 rectangular openings 5 and intersecting these openings are vertical tapering key-ways 6, said key-ways extending from the treads 7 of the rails through the webs 4 and the base flanges 8 of the rails. These key- 60 ways are adapted to receive tapering keys 9.

Mounted against the sides of the rails are splice bars 10 having the inner sides thereof provided with staggered longitudinal arranged sockets 11 and 12, the sockets 11 to 65 be in longitudinal alinement and in a plane above the longitudinal alinement sockets 12. These sockets are adapted to register with the openings 5 of the rails. The inner sides 70 of the splice bars are provided with tongues 13 and 14, the tongues 13 being arranged at the lower edges of the sockets 11 and the tongues 14 at the upper edges of the sockets 12, all of said tongues having vertical rectangular openings 15. The tongues 13 and 75 14 are adapted to extend into the openings 5 and the openings 15 of the tongues 13 of one splice bar are adapted to register with the openings of the tongues 14 of the other splice bar. The registering openings 15 of 80 the tongues provide clearance for the keys 9 driven into key-ways 6 to lock the splice bars in engagement with the rails.

From the foregoing it will be observed 85 that I have devised a rail joint that can be easily and quickly installed without the use of skilled labor, and while in the drawing there is illustrated a preferred embodiment of the invention, it is to be understood that the structural elements are susceptible to 90 such changes as fall within the scope of the appending claim.

What I claim is:—

In a rail joint, rails having the webs thereof provided with transverse openings, 95 said rails having vertical tapering key-ways intersecting said transverse openings and extending from the treads of the said rails to the base flanges thereof, splice bars 100 engaging the sides of said rails, said bars having the inner sides thereof provided with staggeredly arranged and longitudinally alining sockets adapted to register with the transverse openings of said rails, staggeredly arranged and longitudinally 105 alining tongues carried by said bars and adapted to extend into the transverse openings of said rails, said tongues having ver-

tical openings formed therein adapted to register with the key-ways of said rails, tapering keys mounted in said key-ways, and transverse ribs carried by the base flanges of said rails at the ends thereof and adapted to support said rails in an elevated position, substantially described.

In testimony whereof I affix my signature in the presence of two witnesses.

CLAYTON B. FERGUSON.
